UNITED STATES PATENT OFFICE.

JAMES E. PICKLESIMER, OF ATLANTA, GEORGIA.

LAMP ATTACHMENT FOR SADIRONS.

Application filed July 14, 1925. Serial No. 43,558.

This invention relates to an illuminating device for electric appliances, and particularly adapted for use with the standard construction of electric sad irons.

5 It has for its object the provision of illuminating means carried by the iron, and capable of remaining lighted, whether or not the current is passing through the heating element of the iron, for illuminating the work passed over by the iron, particularly in the vicinity of the point thereof.

The invention further contemplates the provision of an electric lamp mounted upon the iron in such a way as to be protected 15 from the violence of vibrations, when the iron is applied with impact to the work.

Another object of the invention is the construction of lamp supporting means by which dirigibility of the light may be obtained as well as variability in the extensiveness of the area of illumination.

A further object of the invention is the provision of a light-supporting bracket which may be applied to any electric iron 25 without the necessity of making any structural alterations therein.

Other objects of the invention will appear as the following description of an illustrative embodiment thereof progresses.

30 In the drawings,

Figure 1 is a perspective view of a standard form of iron equipped with the device of my invention, the portion of the figure in broken lines indicating the switch plug removed from the iron;

Fig. 2 is an exploded view showing the bracket parts;

Fig. 3 is a side elevation of the bracket;

Fig. 4 is an end elevation of the upper 40 or socket clamping end of the bracket;

Fig. 5 is a section through the switch plug;

Fig. 6 is a diagram of the electric connections.

Referring now in detail to the several 45 figures, the numeral 1 represents the iron, which is of standard construction having the handle 2 with thumb piece 3. The handle is secured to the base of the iron by means such as the spaced screws 4.

50 A switch plug 5 makes the usual electrical connection between the terminals of the heating elements of the iron, not shown, and the cord 6 which leads to a wall socket, the heating circuit being made or broken by manipulating the switch 7.

The present invention includes the con-

nection of the electric lamp 8 into the house-line circuit at a point intermediate the house-line circuit and the switch 7 of the heating circuit, so that manipulation of the 60 switch will not affect the status of the lamp circuit. This relative disposition of the heating and lighting circuits is diagrammatically shown in Fig. 6 in which *a* and *b* represent the house-line wires *c* the heating 65 element and *d* the lamp shunt circuit. It is evident that the circuit *c* may be open or closed without affecting the circuit *d*, and that conversely, opening or closing of the lighting circuit does not disturb the heating 70 circuit.

Mechanical means for effecting this circuit arrangement in the switch plug, consists in providing conductive clips 9 and 10 under the screws that connect with the live 75 wires, said clips terminating in resilient prongs, 11 and 12 adapted to make contact, through slots (not shown), in the casing of the switch plug, with terminals, (not shown), which project from the plug 13 into 80 said slots.

The bracket by means of which the light is supported consists of a base 13 adapted to lie between the upright portions of the iron handle and having holes 14 and 15 positioned to register with the screws 4. Said base is fixed in place by screwing it, in common with the iron handle, to the base of the electric iron.

The base 13 is provided with a laterally 90 extending part 15 which is folded upon itself to form an open sided clamping loop 16, shaped to form a seat for adjustably holding the laterally turned end 17 of the bracket rod. A screw 19 and wing nut 20 95 co-act with the clamping loop through an aperture 21, to hold the parts rigid. The main portion of the bracket rod 18 preferably lies in a plane perpendicular to the axis of the laterally turned end 17, so that the 100 lamp swings in a vertical plane, parallel to the longitudinal dimensions of the iron, through the adjustment provided by the clamping loop.

This varies the intensity and area of the 105 field of illumination as well as directs the light more or less forwardly of the point of the iron.

The clamping rod 18 is preferably bent angularly at an intermediate point 22, in a 110 vertical plane, the angle formed by this bend being in a plane perpendicular to the right.

angled bend formed between the laterally turned end 17 and the main portion of the rod. The perpendicular relation of these bends causes the rod substantially to absorb vibrations due to the practice sometimes indulged in of pounding the iron heavily upon the goods being ironed, so that the lamp filament is protected against destruction.

The upper end of the bracket rod 18 is provided with a head 23 having a spherical surface which bears against the matching concave surfaces of the clamping members 24 and 25, forming a ball and socket joint. Said clamping members may be adjusted in any direction with respect to the bracket rod, and held in adjusted position by means such as the screw 26. The clamping members 24 and 25 are provided with band portions 27 and 28 which are adapted to encircle the ordinary lamp socket 29 by means of which the lamp 8 is retained. The band portions 27 and 28 may be formed with recesses 30 and 31 for receiving the key 32 of the lamp socket, although in the drawings the key is shown as accommodated within the space between the ends of the encircling band portions, which do not meet. By means of the universal joint afforded by the head 23 and clamping members 24 and 25, the light may be turned at will to cast its rays on either side of the iron, or forwardly or backwardly, as may be desired.

The lamp 8 is shielded by a shade 33 which is preferably formed with a reflecting surface 34 on the inside. In the preferred construction it is provided with a cylindrical neck 35 which swivels upon the socket outside of the zone of engagement of the encircling portions of the clamping members 24 and 25. The reflector may therefore be turned at will about the axis of the lamp, concentrating the illumination upon any desired area, and at the same time shielding the eyes of the operator from glare.

While I have herein illustrated and described what I believe to be an eminently practical embodiment of my invention, it is to be understood that such changes and alterations may be made in the construction and arrangement of the parts as will not conflict with a broad interpretation of the appended claims, limited only by the state of the prior art.

Having described my invention what I claim as new and desire to secure by Letters Patent, is:—

1. In an electric iron, a handle, a lamp-supporting bracket, means for securing said handle to said iron, said bracket including a base attachable to said iron, said base be-

ing formed with a lateral extension constituting a clamp, said bracket also including a rod oscillatable in a substantially vertical plane and having a lateral portion adjustably securable in said clamp, and a lamp-receiving portion universally jointed with respect to said rod. 65

2. In an electric iron, a lamp-supporting bracket including a base attachable to said iron having a lateral extension constituting a lamp, and a rod angularly bent at two points, in substantially perpendicular planes, one end of said rod being adjustably held by said clamp, and a lamp-receiving portion universally jointed adjacent the other end of said rod. 70

3. In an electric iron, a lamp-supporting bracket including a base attachable to said iron, having a laterally extending portion constructed to form a clamp, a rod angularly bent at two points in substantially perpendicular planes, one end of said rod being adjustably held in said clamp, a substantially spherical head carried adjacent the other end of said rod and lamp socket 85 encircling members having concave recesses cooperable with said head, to form a universal joint, and single means for clamping said members against said head and the socket of a lamp. 90

4. In an electric iron, a lamp-supporting bracket including a base attachable to said iron, having a laterally extending portion constructed to form a clamp, a rod angularly bent at two points in substantially perpendicular planes, one end of said rod being adjustably held in said clamp, a substantially spherical head carried adjacent the other end of said rod and lamp socket 100 encircling members having concave recesses cooperable with said head, to form a universal joint, single means for clamping said members against said head and the socket of a lamp, and a shade for said lamp 105 swivelly carried by said socket. 110

5. An illuminating device for an electrical appliance including a lamp-supporting arm having one end rotatably connected to the appliance and provided at the other end with a lamp universally coupled thereto, to permit the arm to be swung forward and rearwardly to adjust the lamp vertically and longitudinally of the appliance, the universal coupling permitting the lamp to be adjusted vertically and sidewise of the appliance without disturbing the adjustment of the supporting arm. 115

In testimony whereof I affix my signature.

JAMES E. PICKLESIMER.
